UNITED STATES PATENT OFFICE

WEBB SUTER, OF CAMPBELLSBURG, KENTUCKY

SURGICAL TABLE

Application filed August 27, 1931. Serial No. 559,807.

This invention relates to a surgical table primarily adapted for use in connection with the setting of broken legs and arms, although capable of other uses as will herein-
5 after appear.

A particular object is to provide a construction in which the top or supporting surface for the patient consists of longitudinal and transverse elements of cloth, with means
10 for tensioning the same, the cloth being adapted where desired, to be removed and used as part of a bandage about an adjacent fracture.

It is further aimed to provide a novel construction utilizing adjustable crutches for the arms in combination with adjustable elements to which the feet may be fastened.

It is also aimed to provide novel means whereby an arm may be fastened at any desired angle and also a novel top for use when desired, to support the patient for general examination and irrigation.

Various additional objects and advantages will become apparent from a consideration
25 of the description following taken in connection with accompanying drawings illustrating an operative embodiment.

In said drawings:-

Figure 1 is a plan view of the improved
30 surgical table,

Figure 2 is an end elevation looking from
the left in Figure 1,

Figure 3 is a side elevation of the table,

Figure 4 is a cross sectional view taken on
35 the line 4-4 of Figure 3,

Figure 5 is a cross sectional view taken on
the line 5-5 of Figure 1,

Figure 6 is a sectional view taken on the
line 6-6 of Figure 2,

Figure 7 is a sectional view taken on the
line 7-7 of Figure 1,

Figure 8 is a fragmentary perspective view
illustrating a modified form of top applied
to the table, and

Figure 9 is a plan view of a further modified form.

Referring specifically to the drawings, the table comprises a suitable skeleton frame-
50 work generally designated 10, which may be
of any appropriate size or shape and which

is preferably made from various lengths of metal piping 11 detachably connected together by screw engagement with couplings 12. As a result, the construction may be
readily knocked down or collapsed so that it
55 may be carried by the physician from patient to patient, although of course the table may be made up of rigidly connected parts.

Said frame particularly includes end bars
13 and 13' at the top of the table and parallel
60 side bars 15 and 16 at the top of the table. Bar 15 is connected to couplings 14 and 14'
and the latter is in rigid relation with the end bar 13'. Coupling 14, however, constitutes
65 a bearing since the adjacent end of end bar 13 is journaled therein.

The bar 13' has a bracket 17 fastened
thereon in which the side bar or rod 16 is
journaled. Said side bar 16 has a crank 18
70 and a ratchet wheel 19 thereon coacting with
a pawl 20 pivoted to the bracket 17. The
other end of the side bar 16 is journaled in a
bearing 21, which like the bracket 17, is rigidly
75 connected to the frame 10. Bearing 21
constitutes part of a bracket 22. Said end bar 13 is journaled in the bracket 22. An
operating crank or handle 23 is rigid with
bar 13 and a ratchet wheel 24 is also pro-
80 vided thereon and coacts with a pivoted pawl
25 carried by bracket 22.

A patient-supporting top for the table is
shown at 26 which is preferably of textile
fabric and of endless form, trained over the
bars 13 and 13', the former being serrated
85 or roughened as at 27 where the top engages
the same. Through the turning of the crank
23 and rod 16, the top 26 may be tightened or
tensioned to any desired degree to support
the patient without undue sag. The top 26
90 is reenforced by cross webs 28, which are rel-
atively narrow so as not to interfere with ap-
plying casts or the like to the patient. Webs
28 are also preferably endless and of textile
fabric and they pass about the rods 15 and
16, the latter being serrated or roughened
95 as shown at 29 to facilitate engagement there-
with. The turning of the shaft 16 by opera-
tion of the crank 18 serves to tension the
webs 28.

A pair of crutches are carried by the table
100

at 30, extending through and above slits 31 provided longitudinally in the top 26. The crutches are adjustably mounted by means of brackets 32, adapted to be clamped to adjacent rods or parts of the frame 10.

A pair of feet plates are provided as at 33 having screw rods 34 extending therefrom and passing through uprights or brackets 35 which are adjustably fastened by clamps or 0 the like as at 36 to parts of the frame 10.

In the use of the device, for instance in reducing a fractured femur, the patient is disposed on the top 26 and the crutches 30 or one of them is adjusted under the arms or arm 15 of the patient. This prevents the patient from slipping down when traction is put in the foot. A foot or both feet are bandaged to the plates 33 whereupon nuts 37 are tightened until the fracture is reduced. Then 20 plaster of Paris or splints are bandaged around the leg, using part of the top 26 in the bandage, the same being cut or slit as at 38, for that purpose. The cloth is split at 38 before the cast is applied so as to better be in accordance with the width of the leg in order 25 to allow the cloth to fit the leg properly.

It is obvious that the table may be used for various other surgical purposes as will 30 be aware to a surgeon. The invention may further be modified within the spirit and scope.

In Figure 8 for instance, the structure is the same as in the described figures except the top 26 and webs 28 are omitted. In their 35 stead, a sheet metal top 40 is used which has depending flanges 41 overhanging the end bars 13 and 13'. This top is preferably used for general examination purposes or for irrigation, to the latter end, having a depression 40 at 42 to facilitate discharge of fluid.

In the further modified form of Figure 9, the structure is identical with that of Figures 1 to 7 with the exception that one side bar 46, corresponding to that at 15, has an arcuate 45 portion 47, along which a bracket 48 may be adjusted. Said bracket carries a screw 49 having a plate 50, the latter being adjustable through operation of a nut 51 engaging the screw 49. As a result of this feature, an arm 50 of the patient may be secured to the plate 50 and the latter is capable of adjustment to various angles or locations along the deflected portion 47. Also, the rod 46 is preferably removable from the couplings 14 and 14' and 55 reversible end to end, to enable the same plate 50 and deflection 47 to be used for right and left arms by reversing the position of the injured person on the table top.

Various changes may be resorted to provided they fall within the spirit and scope of the invention.

I claim as my invention:

1. A surgical table comprising a frame, end bars thereon at the top, a top member trained about the end bars, one of said end

bars being rotatable to tension the top, side bars, relatively narrow webs passing over the side bars and in supporting engagement with the top member, and means operable to turn one of the side bars to tension said webs. 70

2. A surgical table comprising a frame, end bars thereon at the top, a top member trained about the end bars, one of said end bars being rotatable to tension the top, side bars, relatively narrow webs passing over the 75 side bars and in supporting engagement with the top member, means operable to turn one of the side bars to tension said webs, crutch means extending from the frame through and above said top member, and a plate to which a foot may be secured extending over said top.

3. A surgical table having a frame, an end bar journaled at one end to the top of the frame, another end bar, a bracket secured to the last mentioned end bar, a side bar journaled in said bracket, pawl and ratchet mechanism on said side bar and bracket, another bracket suitably supported in which said first mentioned end bar and said side bar are journaled, and pawl and ratchet 80 mechanism on said first end bar and the second bracket. 85

4. A surgical table having a side bar at the top thereof provided with a deflected portion, a plate to which an arm may be secured, and means for adjustably mounting said arm for movement with respect to said portion. 95

5. A surgical table, comprising a frame including coupling members, a side bar removably mounted in said coupling members and provided with a deflected portion, a plate to which an arm may be secured, and means for adjustably mounting the arm for movement with respect to the portion, the side bar being adapted to be reversed in position relatively to the coupling members. 100

6. A surgical table, comprising a supporting frame including a cross bar, a crutch member secured to the cross bar, and a top member made of flexible material and having an elongated opening therein receiving said crutch. 110

In testimony whereof I affix my signature.
WEBB SUTER.
